CONICAL ELECTRIC BURNER

Warren Noble, Detroit, Mich., assignor to Electromaster, Inc., a corporation of Michigan

Application October 10, 1931, Serial No. 567,994

6 Claims. (Cl. 219—19)

This invention relates to electric burners for electric stoves, and particularly to burners of the conical type.

An object of my invention is to provide an improved form of connector for connecting the ends of a pair of resistor wire heating elements to avoid overheating, cracking and ultimate destruction of the connection in service.

It is a further object of my invention to provide an improved form of connector for connecting the ends of a pair of resistor wire heating elements to a common terminal intermediate the ends of the heater circuit.

It is also an important object of my invention to provide a conical electric burner having a plurality of separate spiral grooves so that a plurality of resistor wire heating elements may be placed in position in the grooves for selective and independent operation.

Other and further important objects of my invention will be apparent from the disclosures in the following specification and accompanying drawing.

In the drawing:

Figure 1 is a sectional view, with parts in elevation, of a conical electric burner embodying the principles of my invention.

Figure 2 is a side view in elevation of my improved connector, with parts broken.

Figure 3 is a part sectional view of a conical electric burner, with parts in elevation to show details of electrical connections.

Figure 4 is a top view of the burner.

This application is, in part, a continuation of my Patent No. 1,881,881, issued October 11, 1932, and entitled "Heating element".

As shown in the drawing:

The numeral 10 indicates a hollow conical body of refractory material. A pair of spiralled resistor wire heating elements 11 and 12 are wound on the exterior face of the cone and are each positioned in a separate and continuous spiralled groove extending from the base to the tip of the cone.

Referring to Figure 3, the cone 10 has a slot 13 in a depending integral annular portion 14, and this slot 13 enters the starting end of a groove 15 in which the heating element 11 is placed. Directly opposite the slot 13 is another slot 16 which enters the starting end of another groove 17 in which the heating element 12 is positioned. These grooves extend to the top end of the cone, where an end of each of the heating elements passes through slots 18 and 19 and enter a recess 20 in the head of the cone. The

two ends 21 and 22 are welded together at 23, Fig. 2, and are also welded to a connector 24 of suitable material.

If the ends 21 and 22 are merely welded together, it is a very difficult matter to form the joint so that its resistance and expansibility is similar to that of the wires, and the joint is likely to form a "hot spot." Welding also is likely to unduly stiffen the wires about the joint, so that, with the temperature changes experienced in service, the wires are likely to crack at or close to the joint.

I have found that the connector 24, now to be more fully described, securely anchors the ends of the heating elements and eliminates undue heating at the joint and the breaking of the wires at or near the joint.

The connector 24 may be formed of a substantially rectangular thin strip of metal which is cut to provide an intermediate depending apron 25 and end wing portions 26, which are bent over the wire ends 21 and 22 and pressed, tightly clamping the wires to anchor them. As shown in Figure 1, the clamping wings 26 are positioned in the slots 18 and 19 and rest on the body of the cone 10. The apron 25 is slightly bent or curved to lie snugly against a terminal rod 27, to which it is spot-welded at 27a near the tip of the rod.

The ends 21 and 22 of the resistor wires are curved between the clamping wings 26 and where they are welded together and to the apron at 23 to provide for expansion and contraction due to temperature changes so that there is no strain on the weld.

Integrally formed on the interior of the cone 10 are a plurality of ribs 28 which enter between spaced upstanding lugs 29 formed on a terminal block 30, of refractory material which is adapted to cooperate with a suitable terminal socket (not shown). The ribs 28 also abut the upper surface of the block 30, whereby the cone 10 is supported on the block 30, but is not rigidly connected thereto.

The rod 27 passes through an aperture 31 in the block 30 and is secured to the block by means of a nut 32 threaded on the rod, and an enlarged portion or integral extending arms 33 seated on the block in a suitably shaped recess 34 formed in the block. A resilient lock washer 35 is interposed between the nut 32 and the lower face of an integral depending neck portion 36 of the block 30.

It will be evident that the block 30 serves as a support for the rod 27. The length of the

rod 27 is so adjusted that, when the rod is heated and has expanded, the cone 10 is free for limited axial movement on the rod between the connector 24 and the block 30, thereby relieving the parts of any stresses which might be set up by virtue of the expansion and contraction thereof due to temperature changes.

The starting end of the heating element 11 is suitably connected to a ring 37 of wire coiled around an enlarged portion 38 of the neck 36, and the starting end of the heating element 12 is suitably connected to a wire ring 39 coiled about the neck 36.

It will be evident that the burner may be connected to a three-wire system with the rod 27 connected to the neutral, and that the heating elements may also, by simple switch means, be connected to operate in parallel, or in series, or singly, as desired.

20 It will be understood that the two heating elements 11 and 12 may, in fact, consist of a single spiralled wire element having a non-spiralled portion thereof for connection to the rod 27. The elements would then be connected 25 to the rod 27 by spot-welding the straight portion of the wire to the apron 25.

The connector 24 provides means for anchoring spaced apart portions of the wire so that no strain is thrown on the weld as the heating 30 elements expand and contract, and so that the straight portion of the wire may be bent to form an expansible loop about the weld. The apron 25 also provides ample heat and current 35 conducting surface to keep the welded connection between it and the wire relatively cool, and, at the same time, it provides means for connecting the wire to the rod 27 by another welded connection.

I am aware that many changes may be made, 40 and numerous details of construction may be varied through a wide range without departing from the principles of this invention, and I, therefore, do not purpose limiting the patent granted hereon otherwise than necessitated by 45 the prior art.

I claim:—

1. An electric burner comprising a body supported for axial movement, heating elements on said body having a common section, means 50 anchoring the common section of said heating elements, said means comprising a connector having spaced portions clampingly engaging spaced portions of said section and having an intermediate portion secured to a looped portion of said section intermediate its clamped portions.

2. An electric burner comprising a body, heating elements on said body having a common connection at adjacent ends, means anchoring the adjacent ends of said heating elements, said 60

70

75

body having a recess, said anchoring means comprising a connector having spaced parts clampingly engaging spaced portions of said common connection, and having an intermediate portion entered in said recess.

3. An electric burner comprising an elongated body, heating elements on said body having a common connection at adjacent ends, said body having a recess at one end thereof and having slots communicating with said recess formed in a wall thereof, means anchoring the adjacent ends of said heating elements, said means comprising a connector having parts in said slots clampingly engaging spaced portions of said common connection, and having an intermediate portion entered in said recess.

4. An electric burner comprising an elongated hollow body having a closed end with an aperture therein, a heating element on said body, a terminal block disposed in the other end of said body, said block and body having a sliding engagement, a terminal rod carried by said block extending thru said aperture and electrically connected to said element, whereby said body may be axially moved relative to said block and 100 rod, and means to limit said movement.

5. An electric burner comprising a refractory hollow cone shaped body having an apertured closure inwardly disposed from its small end, a pair of diametrically opposed slots at said end, 105 a terminal block disposed in the large end of said body, said block and body having a sliding engagement, a terminal rod carried by said block extending thru said aperture, whereby said cone may be axially moved relative to said block and 110 rod, a wire heating element on said cone extending thru said slots, a connector secured to an end of said rod and having parts in said slots clampingly engaging spaced portions of said wire, and means to limit the axial movement of said body. 115

6. An electric burner comprising a refractory hollow cone shaped body having an apertured closure inwardly disposed from its small end, a pair of diametrically opposed slots at said end, a terminal block disposed in the large end of 120 said body, said block and body having relative axial movement, lugs on the interior of said cone disposed to abut said block, a terminal rod carried by said block extending thru said aperture, a wire heating element on said cone extending thru said slots, and a connector secured to an end of said rod having oppositely extending 125 arms disposed for movement longitudinally of said slots, said arms being clamped to spaced portions of said wire, said lugs and arms cooperating to limit the axial movement of said cone, whereby said cone is supported free of compression.
